UNITED STATES PATENT OFFICE.

HOWARD E. WATKINS, OF NEW YORK, N. Y., ASSIGNOR TO OXLEY ENOS COMPANY, OF NEW YORK, N. Y., A CORPORATION OF NEW YORK.

DESIGN FOR A BRACKET GAS-FIXTURE.

SPECIFICATION forming part of Design No. 36,183, dated December 30, 1902.

Application filed November 29, 1902. Serial No. 133,290. Term of patent 7 years.

To all whom it may concern:

Be it known that I, HOWARD E. WATKINS, a citizen of the United States, and a resident of New York city, borough of Manhattan, county of New York, and State of New York, have invented and produced a new, original, and ornamental Design for Bracket Gas-Fixtures, of which the following is a specification, reference being had to the drawing accompanying and forming a part of the same, which is a perspective view showing the design.

This design comprises a rosette A, the outer portion of which has a wavy outline, as indicated, and comprises a beaded ground or border upon which are arranged the spirally-disposed leaf elements B. Within the border is a row of beading C, which separates it from the raised boss D, having a smooth convex surface. From the center of this boss rises the spherical support E, from the lower portion of which depends the conventional leaf element F. From the upper portion of this support E there rise the fluted arms G, having the compound - curved formation shown in the drawing, these arms being enriched by the spiral design of conventional foliage H, indicated. Each arm is interrupted near its outer extent by the spherical bulb I, from which depends the tulip-shaped

ornament K. At the outer ends of each of these arms the annular fillet L is arranged, and above this fillet is the dish-shaped rosette M, having a fluted edge, as indicated. This rosette comprises the convex central 35 boss N, having a smooth surface and the outward flaring portion, which is ornamented by the convex separated spirally-arranged beading O, the pitch of this beading gradually increasing from the center to the edge of 40 the rosette, the beading merging in each instance into the detached spherical beads O, which continue the line of beading. Above this rosette M there rises the calyx-shaped ornament Q, having the fluted edge S and 45 comprising the smooth-surfaced oval-shaped lower end P and the separated spirally-arranged beading R, terminating at the upper end of the beading in the detached beads indicated. Above this ornament the arm carries 50 the dish-shaped drip-cup T and the conventional candle U.

What is claimed as new is—

The ornamental design for a bracket gas-fixture, substantially as shown and described. 55
